UNITED STATES PATENT OFFICE

CHARLIE WESTERLUND, OF SAN ANTONIO, TEXAS

TOY

Application filed May 6, 1929. Serial No. 360,838.

This invention relates to toys and is more particularly directed to that type which will support a child and permit the child through the movement of its body to cause the toy to assume various positions simulating the movements of a bucking bronco.

An object of the invention is the provision of a toy in the form of a miniature horse supported by a steel spring in such a manner that by the proper manipulation of the horse by a child seated thereon, the horse will simulate a bucking bronco.

A further object of the invention is the provision of a toy having a body member in the form of a horse adapted to be straddled by a child, a steel spring in the shape of an oblate curve having bearings at the ends in fixed supports, with the body secured at points on the spring intermediate the ends thereof.

In the accompanying drawings forming a part of this application and in which like numerals are employed to designate like parts throughout the same,

Figure 1 is a side elevation of a toy constructed according to the principles of my invention,

Figure 2 is a view in group perspective of a supporting means for one end of a spring forming an element of the invention,

Figure 3 is a plan view of the toy,

Figure 4 is a transverse vertical section taken along the line 4—4 of Figure 1,

Figure 5 is a transverse vertical section taken along the line 5—5 of Figure 1,

Figure 6 is a side view in elevation of a modified form of the invention,

Figure 7 is a side view in elevation of another modified form of the invention.

Referring more particularly to the drawings, 10 generally designates a body member simulating a horse in miniature but of sufficient size to support a child in a saddle 11. Straps 12 are secured to the body in any approved manner and carry stirrups 13 to receive the feet of the child. A buckle 14 is provided for adjusting the straps and stirrups to the proper height to accommodate children of different sizes. A strap or reins 15 are secured to the head 16 and extend to

the saddle to aid in maintaining the child in position and to give the complete effect of a ride on horseback.

Referring to Figure 4 it will be seen that the greater portion of the body is formed of hard wood although the same may be stamped from metal. The front and hind legs 20 and 21 respectively are secured to the body portion in any approved manner as by screws and cemented by glue. Side plates 22 are not only attached to the body but to the upper portions of the legs in a reinforcing manner.

The intermediate portion of a spring 23 is secured to the body by a pair of U-bolts 24 passing through longitudinally disposed blocks 25 and 26. A U-shaped steel plate 27 rests upon the block 25 and engages the nuts 28 threaded onto the ends of the U-bolts for protecting the block 25 against wear. A leather buffer 29 is placed between each bight of a U-bolt and the spring 23 to prevent excessive wear on the associated parts.

One end 30 of the spring 23 is formed into a sleeve to receive a bolt 31 inserted through passages 32 in ears 33 carried by a post 34 adjustably positioned in a hollow standard 35. The standard has a flange 36 which is secured to an elongated base member 37 mounted on blocks 38. The standard is provided with passages 39 adapted to be aligned with passage 40 in the post 34 and a pin or bolt 41 is received by the passages for vertically adjusting the post and compensating for various elevated positions of the body 10. Thus it will be seen that the toy may be adjusted to accommodate children of different sizes.

The opposite or rear end 42 of the spring 23 is curved rearwardly and formed into a sleeve 43 to receive an axle 44 carried by rollers 45 mounted in spaced guides 46. The ends of the axles project through slots 47 in said guide. The guides are secured to the base 37.

Referring more particularly to Figure 6 it will be seen that a modified form of the invention is illustrated. A body member 50 simulating a horse is secured by means of bolts 51 to a curved spring 52 which has its ends pivotally connected at 53 to straps 54 suspended from the ends 55 of curved rods

56. Each rod is slidably mounted in a hollow post having perforations 58 alining with passages in a rod 56 and a cotter pin 59 inserted through the passages and perforations will retain the vertical adjustment of the rods. The posts are secured at 60 to the opposite ends of a base member 61.

10 In Figure 7 is shown a further modified form in which a body member 70 is connected by means of U-bolts 71 to the intermediate portion of a curved spring 72 formed of flat metal. The ends of the spring are formed into sleeves which receive pins 73 carried by brackets 74. These brackets are secured to 15 an elongated base member 75 supported at its ends on block 76. Stirrups 77 and reins 78 are provided for the body members 50 and 70 respectively illustrated in Figures 6 and 7.

20 20 The operation of my device is as follows: After a child has been seated in the saddle either the post 34 in Figure 1 is adjusted to the proper height or the rods 56 in Figure 6 are raised or lowered. The feet are 25 inserted in the stirrups and the reins are grasped. The child by rocking his body back and forth causes the body of the horse in any form illustrated to assume various positions simulating the actions of a bucking 30 bronco. Forward movement of the body tends to flex the front and rear portions of the spring which supports the body in opposite directions so that the forward portion of the spring tends to flex or bulge outwardly while the rear portion is flexed inwardly. 35 A rearward motion of the body causes a reverse action in the portions of the spring. Continued movement in opposite directions provides for more rapid and intensive compression and rebound of the portions of the 40 spring so that the body of the toy will assume quickly inclined positions in approximately the same manner as a bucking bronco.

45 In fact, the rear end of the spring 23 in Figure 1 has a sliding movement so that the inclined positions in this form, will be greatly accentuated and the tendency for the body to move to a state of equilibrium will be less and the bucking characteristics will therefore 50 be more evident.

Having thus described the invention, what is claimed is:

55 1. A toy comprising a body member, a curved spring, means for securing the body member to an intermediate portion of the spring, spaced supports for the ends of the spring, one end of the spring being slidably mounted in its support.

60 2. A toy comprising a body member, a curved spring, means for securing the body member to an intermediate portion of the spring, spaced supports for the ends of the spring, the ends of the spring being pivotally mounted in its supports, the pivotal 65

mounting for one end of the spring being slidable in its respective support.

70 3. A toy comprising a body member, spring means projecting outwardly and downwardly in opposite directions from the center of gravity of the body member, means for pivotally supporting the ends of the spring means, the portion of the spring means at one side of the body being adapted to be flexed in the opposite direction from the portion of the spring means at the opposite sides of the body, the pivotal mounting of one end of the spring having a limited sliding move- 75

80 4. A toy comprising a body member, a curved spring means extending from sides of the body member and resiliently supporting the body for swinging and tilting movements, a pivotal mounting for one end of the spring means, rollers, an axle supported by 85 the rollers and having pivotal connections with the other end of the spring means, and a support for the rollers permitting limited horizontal movement of said rollers and axle.

90 5. A toy comprising a body member, a curved spring means extending from sides of the body member and resiliently supporting the body for swinging and tilting movements, a pivotal mounting for one end of the spring means, rollers, an axle supported by 95 the rollers and having pivotal connections with the other end of the spring means, and a support for the rollers permitting limited horizontal movement of said rollers and axle, and means for varying the vertical position 100 of the pivotal mounting of the first mentioned end of the spring means.

In testimony whereof I affix my signature.
CHARLIE WESTERLUND.
